UNITED STATES PATENT OFFICE.

EDWIN P. SEARS, OF BUFFALO, NEW YORK.

BUCKLE.

SPECIFICATION forming part of Letters Patent No. 268,550, dated December 5, 1882.
Application filed July 24, 1882. (No model.)

To all whom it may concern:

Be it known that I, EDWIN P. SEARS, of the city of Buffalo, in the county of Erie and State of New York, have invented new and useful 5 Improvements in Buckles, of which the following is a specification.

This invention relates to that class of buckles which are provided at one end with a hook or bent portion around which the strap is bent, 10 and by which the bent portion of the strap is supported and relieved from wear.

The object of this invention is to construct the buckle in such manner that both ends of the strap can be readily and securely attached 15 thereto and be adjusted thereon, thereby adapting the buckle especially for connecting both ends of hame-straps.

My invention consists, to that end, of the particular construction of the buckle, as will be 20 hereinafter described, and pointed out in the claims.

In the accompanying drawings, Figure 1 is a longitudinal section of my improved buckle applied to a strap. Fig. 2 is a top plan view 25 thereof with one end of the strap turned sideways to expose the buckle. Fig. 3 is a plan view of the buckle with the strap removed.

Like letters of reference refer to like parts in the several figures.

30 A, A represent the curved side bars of the buckle-frame, having their front ends connected together and bent upwardly and backwardly, so as to form a hook, B.

c represents a cross-bar arranged on the under side of the side bars, A, near the hook B.

d represents a cross-bar arranged nearly midway between the ends of the buckle-frame; and e represents a tongue pivoted to the cross-bar d, and having its free end turned toward 40 the hook B.

f represents a cross-bar arranged between the cross-bar d and the hook B, and adapted to support the free end of the tongue e, the latter bearing against the under side of the cross-bar f, as clearly shown in Fig. 1.

g represents a cross-bar arranged in rear of the cross-bar d; and h represents a tongue pivoted to the cross-bar g, and having its free end turned toward the rear end of the buckle-frame.

i represents a cross-bar, which connects the rear ends of the side bars, A, of the buckle-frame, and which supports the free end of the tongue h, the latter bearing against the under side of the cross-bar i.

One end of the strap K is attached to the buckle by means of the tongue e and cross-bars d and f. The strap runs forwardly from the cross-bar f and through the opening between the cross-bar c and the hook B, thence 60 around the hook and back between the side bars, A, of the buckle-frame, and underneath the cross-bar i, which connects said side bars at their highest point. The strap runs thence through the hame ring or loop or other part to 65 which it is attached, and which is not shown in the drawings, and thence backward and over the cross-bar i, where it engages with the tongue h, whereby it is securely attached to the rear end of the buckle. The end of the strap 70 is inserted between the cross-bar c and the adjacent portion of the strap, as clearly shown in Fig. 1.

It is obvious from the foregoing that both ends of the strap are securely attached to the 75 buckle, and that either end can be readily adjusted on the buckle, as may be required.

The buckle herein described and shown forms a neat and substantial means of connecting the two ends of the strap, and does away with 80 sewing or otherwise securing the buckle to the strap.

I am aware that it has been proposed to provide buckles of this class with a button, to which one end of the strap is secured, and this 85 I do not claim; but

I claim as my invention—

1. A buckle composed of side bars, A, having their connected front ends provided with a hook, B, a cross-bar, d, provided with a pivoted tongue, e, a cross-bar, f, arranged between the bar d and the hook B, and adapted to support the free end of the tongue, a cross-bar, g, arranged in rear of the cross-bar d, and provided with a pivoted tongue, h, and a cross-bar, i, connecting the rear ends of the side bars, A, and adapted to support the free end of the pivoted tongue h, substantially as set forth.

2. A buckle composed of side bars, A, having their connected front ends provided with 100

a hook, B, a cross-bar, *d*, provided with a pivoted tongue, *e*, a cross-bar, *f*, arranged between the bar *d* and the hook B, and adapted to support the free end of the tongue, a cross-bar, *g*, arranged in rear of the cross-bar *d*, and provided with a pivoted tongue, *h*, and a cross-bar, *i*, connecting the rear ends of the side bars,

A, and adapted to support the free end of the pivoted tongue *h* and cross-bars *e* and *l*, substantially as set forth.

EDWIN P. SEARS.
